BUILDING MATERIAL

Gilbert Midby, Whitefish, Mont.

Application July 29, 1932. Serial No. 626,108

2 Claims. (Cl. 20—4)

The invention has relation to building material for log houses, having for an object to provide a use for lodge pole timber which is of little value for square timber owing to its small size. Another object is to provide such a building material wherein the logs will not split or chock open to admit water, which causes rotting. Another object is to provide an insulation means against the entrance of water between the logs and also against the entrance of air between the logs. Another object is to provide logs for use with such insulation means, said logs reversible end for end to match up for thickness of the logs. Another object is to provide building material of the natural logs which shall be lasting and also economical in first cost and labor cost in the construction of the side walls of a house. Another object is to provide such a building material which after being set up in a house, is adapted to be taken down and transported and reassembled in another location or stored without substantial damage thereto.

The invention consists in the novel construction and combinations of parts, as set forth in the appended claims.

In the accompanying drawing illustrating the invention, Figure 1 is a cross section of a portion of the side wall of a house constructed in accord with my invention. Figure 2 is a detail perspective view of a portion of one of the half logs used.

In the drawing, the numeral 1 designates the half logs, each formed from the entire log centrally and longitudinally divided through the heart thereof, and provided with vertical inner faces 2, and upper and lower horizontal faces 3, intersecting the vertical faces at right angles, whereby the half logs are adapted to be piled upon one another to provide a continuous vertical inner wall face.

Located at the intersection of the convex outer face 4, of each half log with the upper and lower horizontal faces thereof are provided vertical grooves or dados 5, of the width of the saw used in making the same, the grooves of adjacent half logs registering, and in the groove of the upper half log of each pair of half logs is located a longitudinal vertical insulation strip 6 of metal, having a lower outwardly bent apron portion 7, resting upon the upper part of the outer side of the lower half log of the pair, to which it is nailed at 8, thereby preventing all moisture from getting in between the half logs, which would tend to cause rotting of the wood.

The upper and lower horizontal faces of the half logs are also provided with vertical grooves

9, intermediately of the widths of said faces and of dimensions one half inch by one half inch approximately in cross section, the grooves of adjacent half logs registering.

Due to the fact that a log which is not split open centrally through the heart thereof lengthwise is not adapted for use as building material as it will split or chock open to admit moisture, the lodge pole timber used herein is split or sawed lengthwise centrally thereof and the half logs 65 squared on top and bottom as stated, the finished dimensions of each half log being about four by six inches in cross section.

The dados or grooves 5 and the grooves 9 are made in both upper and lower faces of each half log, so that should the half logs vary in thickness, they may be reversed end for end, with the natural side still outward, to match better for thickness, after which the longitudinal strips 6 may be inserted in the related grooves to the 75 same advantage.

The side walls of a log house so constructed may be readily taken down or dismantled, and reassembled in another location, or stored, with little or no damage to the material used.

The building material shows the natural log and appeals to the public, and should the natural log effect be desired also for the interior walls of the house, this can be readily accomplished by merely duplicating the structure for the inside 85 walls of the house.

In finishing the inside walls of the house with plaster board, celotex or the like, rather than with the natural log effect, the strips of plaster board or celotex may obviously be nailed to uprights or 90 furring strips (not shown) suitably secured to the inner vertical face of the wall.

Standard size logs may be used instead of lodge pole timber, and the dimensions of the grooves and strips may be varied without de- 95 parting from the spirit of the invention.

I claim:

1. Building material, comprising half logs formed of the entire logs centrally and longitudinally divided through the heart thereof and 100 having vertical inner faces, upper and lower horizontal faces intersecting said inner faces at right angles whereby the half logs are adapted to be piled upon one another to form a continuous vertical inner wall face, said half logs at the intersections of the horizontal faces with the convex outer faces of the half logs being provided with vertical grooves of the width of the saw used in making said grooves, and a longitudinal vertical insulation strip of metal fitting in the groove of 110

the upper half log of each pair of half logs and having a lower outwardly bent apron portion resting upon and secured to the upper portion of the outer side of the lower half log of the pair.

5 2. Building material, comprising half logs formed of the entire logs centrally and longitudinally divided through the heart thereof and having vertical inner faces, upper and lower horizontal faces intersecting said inner faces at right angles whereby the half logs are adapted to be piled upon one another to form a continuous vertical inner wall face, said half logs at the intersection of the horizontal faces with the convex

outer faces thereof being provided with vertical registering grooves of the width of the saw used in making the same, a longitudinal vertical metal insulation strip fitting in the groove of the upper half log of each pair of half logs and having a lower outwardly bent apron portion resting upon and secured to the upper portion of the outer side of the lower half log of the pair, said half logs having also intermediately of the widths thereof vertical registering grooves, the half logs being reversible end to end to match for thickness.
